UNITED STATES PATENT OFFICE.

ANDREW J. POEHNER, OF CINCINNATI, OHIO.

IRONING-BOARD SUPPORT.

SPECIFICATION forming part of Letters Patent No. 694,779, dated March 4, 1902.

Application filed October 21, 1901. Serial No. 79,423. (No model.)

To all whom it may concern:

Be it known that I, ANDREW J. POEHNER, a citizen of the United States of America, and a resident of Cincinnati, in the county of Hamilton and State of Ohio, have invented certain new and useful Improvements in Ironing-Board Supports, of which the following is a specification.

This invention relates to certain improvements in supports for ironing-boards and the like, and has for its object to provide a support of this character of a simple and inexpensive nature and of a light, strong, and durable construction capable of being compactly folded up when not in use, so as to occupy a minimum of space, and adapted to be readily and quickly unfolded to form a secure and rigid support for the ironing-board.

The invention consists in certain novel features of the construction, combination, and arrangement of the several parts of the improved ironing-board support, whereby certain important advantages are attained and the device is made simpler, cheaper, and otherwise better adapted and more convenient for use, all as will be hereinafter fully set forth.

The novel features of the invention will be carefully defined in the claims.

In the accompanying drawings, which serve to illustrate my invention, Figure 1 is a side elevation showing the improved ironing-board support as it appears when unfolded and in position for use. Fig. 2 is a side elevation showing the support as it appears when folded together. Fig. 3 is a plan view of the improved support, a portion of the ironing-board carried thereon being broken away in order to show the parts beneath it. Fig. 4 is a vertical section taken through the improved support in the plane indicated by line *a a* in Fig. 1.

The improved support is constructed with a flat base or frame 1, adapted to rest upon the floor. This base may have any desired form and may be formed of a single piece or of a number of pieces suitably connected together. The base or frame 1 is formed with an undercut guideway extended lengthwise along its central part, and in the opposite end portions of said guideway are arranged dovetail slides 2, adapted for endwise sliding move-

ment toward and away from each other. The body portions 3 of the slides 2 are of reduced thickness; but the outer end portions thereof are of a thickness sufficient to permit said outer ends to rest upon the floor, as indicated in Fig. 1, when the slides are drawn away from each other and protrude beyond the ends of the base or frame 1. The base or frame has at its ends recesses for receiving said thicker outer ends of the slides when they are pushed toward each other, and by this means when the support is folded up the ends of the slides are flush with the ends of the base or frame 1. The body portions 3 of the dovetail slides are slotted longitudinally, as indicated at 4 in Fig. 3, and in their slots are engaged pins or studs 5, carried on the base or frame 1 and adapted to form stops to limit the endwise movement of the slides away from each other.

At the corners of the base or frame 1 are upwardly-extended lugs 6, and the lugs at each end of the said base or frame are provided with bolts or pins whereon are pivotally held the lower ends of legs 7. The legs 7 at each end of the frame form a pair, which are connected at their upper parts by a cross-piece 8, which has a central bracket 11, provided with forks, between which is pivotally held the upper end of a brace 10, the lower end of which has pivotal connection with a bracket or lug 9, carried on the outer end of the slide 2 at that end of the base or frame.

At one end of the frame the upper ends of the legs 7 are extended up above the cross-piece 8 and near their extremities carry a bar or rod 12, the ends of which are journaled in the said legs, so that the bar or rod is adapted for turning or pivotal movement, and at 90° the center of said bar or rod is arranged a bolt or pin 13, on the upper end of which is pivotally held a cleat 14, secured to and extended transversely across the wider end of the ironing-board 15. By this means it will be seen that the ironing-board is adapted for pivotal movement in either a vertical or lateral direction. The upper ends 17 of the legs 7 at the other end of the base or frame are also extended up above the cross-piece 8 and carry a rung 16, on which the other free end of the ironing-board 15 is adapted to freely

rest, the upper extremities of said legs above said rung 16 forming stops to prevent lateral movement of that end of the ironing-board when rested upon the rung, so that when the 5 board is in use it cannot be accidentally pushed off the rung at its free end.

For holding the ironing-board folded upon the support when the device is folded up, as indicated in Figs. 2 and 3, angular spring-catches 18 are employed, pivoted on plates 19, secured to the ends of the base or frame 1 and adapted when the device is folded up to take over the edges of the ironing-board near opposite ends thereof to hold the same 15 securely upon the base 1.

In using the improved support, when the same is folded up and it is desired to unfold it the catches 18 are first disengaged from above the ironing-board, after which the slides 2 at 20 opposite ends of the frame or base are drawn out from their guideway until they project from the opposite ends of the base or frame, as indicated in Fig. 1. This endwise movement of the slides 2 will be possible only after the 25 legs 7 are raised up from off the base or frame, and when such movement is effected it acts to draw the braces 10 out of line with the legs 7 at their lower ends, so that the braces serve to securely and rigidly hold the legs in 30 their raised positions. The ironing-board 15, being pivotally connected with the legs at one end of the base or frame, will of course be automatically raised off the base when the legs are raised, and its free end will be engaged between the extended upper ends 17 of 35 the other legs 7 and rested upon the round 16, connecting said legs. Since the free end of the board 15 is only rested loosely upon the rung 16, it is obvious that it may readily 40 be raised to permit garments to be passed around the board, as is necessary for ironing skirts, shirts, &c., and this use of the board is greatly facilitated by the universal pivot connection between the larger end of the 45 board and the legs 7.

When it is desired to fold the device up, it is only necessary to raise the free end of the ironing-board 15 from off the rung 16 and to 50 push the slides 2 toward each other in their guideway, so as to bring the braces 10 into alignment with the legs 7, whereupon the legs are no longer held upright, but are permitted to drop or fall freely to a horizontal position, as indicated in Fig. 2, whereupon 55 the folded device may be securely held in po-

sition by means of the spring-catches 18, above described.

From the above description it will be seen that the improved ironing-board support is of an extremely simple and inexpensive nature and is especially well adapted for use, since it is adapted for rigidly and securely supporting the ironing-board when in use and is also capable of being compactly folded up when not required for use. It will also 65 be obvious from the above description that the device is capable of considerable modification without material departure from the principles and spirit of the invention, and for this reason I do not wish to be understood as limiting myself to the precise form and arrangement of the several parts of the device herein set forth.

Having thus described my invention, I claim—

1. A support of the character described comprising a base or frame, legs pivotally connected therewith and adapted to be raised and lowered and having their upper ends adapted to support an ironing-board, slides movable 80 on the base or frame, braces pivoted on the slides and having loose connection with the legs for holding them in raised position, said braces having their pivotal connections with the slides adapted, in the movement of said 85 slides, to be moved in and out of alignment with the pivotal connections of the legs with said base or frame and means to limit the movement of said slides, substantially as set forth.

2. A support of the character described comprising a base having a longitudinal dovetail groove, legs pivoted on the base and adapted to be raised and lowered and having upper ends adapted to support an ironing-board, dovetail slides movable in the groove of the base and formed with longitudinal slots, pins on the base engaged with said slots to limit the outward movement of the slides, and braces pivoted on the slides and having 95 loose connection with the legs for holding them in raised position, substantially as set forth.

Signed at Cincinnati, Ohio, this 16th day of October, 1901.

ANDREW J. POEHNER.
